UNITED STATES PATENT OFFICE.

JOSEPHINE BECKER, OF BROOKLYN, NEW YORK.

GAME APPARATUS.

No. 806,624.

Specification of Letters Patent.

Patented Dec. 5, 1905.

Application filed August 8, 1905, Serial No. 273,264.

To all whom it may concern:

Be it known that I, JOSEPHINE BECKER, a citizen of the United States, residing at Brooklyn, in the county of Kings, State of New York, have invented certain new and useful Improvements in Game Apparatus; and I do hereby declare the following to be a full, clear, and exact description of the invention, such as will enable others skilled in the art to which it appertains to make and use the same.

This invention relates to game apparatus.

One object of the invention is to provide a parlor game embodying such characteristics as to afford amusement or excitement to the participants.

Another object of the invention is to provide an exceedingly simple and inexpensive game apparatus.

With these and other objects in view the present invention consists in the combination and arrangement of parts, as will be hereinafter more fully described, shown in the accompanying drawings, and particularly pointed out in the appended claim, it being understood that changes in the form, proportion, size, and minor details may be made within the scope of the claim without departing from the spirit or sacrificing any of the advantages of the invention.

In the drawings, Figure 1 is a perspective view of the tray. Fig. 2 is a perspective view showing one of the dice in two positions. Fig. 3 is a view of a number of chips.

In order to play the game invented by me, I provide a tray 1, divided into a series of six compartments 2 of various colors, as green, yellow, black, red, white, and blue. These compartments may be colored in any order desired. Six dice 3 are used, each die having six sides and each side of each die being colored according to the colors of the six trays. I also provide a number of chips 4—say, for instance, six hundred in all—so that there may be one hundred chips for each color of the series of compartments of the tray 1, the colors of the chips of course corresponding also to the colors upon the dice.

Upon starting the game each player receives an equal number of chips of different colors according to the colors of the series of compartments 2. We will suppose that five persons are in the game, in which event each player will receive twenty chips each of green, yellow, black, red, white, and blue. Then each player in turn will throw the six dice, the object being to throw the dice so that one of each of the six colors will turn up. If the player fails to throw any one of the colors, he must place a chip of the color not thrown in the compartment of the tray corresponding to the color not thrown. For instance, supposing the player threw two green, two red, and two blue sides of the dice, he would then have to forfeit two chips to the green, red, and blue compartments. The successful thrower gets all the chips in the compartment or in the event that he should be successful in his first throw he is entitled to one-half of all the other chips which his opponents may possess. The winner of the game is the person having all or most of the chips at the conclusion of the game.

From the foregoing it will be seen that I provide a game tending to create more or less excitement, and therefore afford amusement to those participating in the game.

What is claimed is—

A game apparatus comprising a tray divided into a series of compartments of different colors, a series of six dice, each die being six-sided with the sides thereof colored according to the colors of the compartments, and a number of chips of different colors corresponding to the colors of the dice and compartments for disposition within the compartments of like color.

In testimony whereof I affix my signature in presence of two witnesses.

JOSEPHINE BECKER.
